UNITED STATES PATENT OFFICE.

CHARLES M. PRIOR AND CHARLES NELSON, OF NEW YORK, N. Y., ASSIGNEES TO S. STERNAU & COMPANY, OF BROOKLYN, NEW YORK, A COPARTNERSHIP.

DESIGN FOR A CHAFING-DISH AND STAND.

43,060.

Specification for Design.

Patented Sept. 24, 1912.

Application filed June 2, 1911. Serial No. 630,906. Term of patent 7 years.

To all whom it may concern:

Be it known that we, CHARLES M. PRIOR, a citizen of the United States, and a resident of the borough of Manhattan, city, county, and State of New York, and CHARLES NELSON, a citizen of the United States, and a resident of the borough of Brooklyn, county of Kings, city and State of New York, have invented a new, original, and ornamental Design for a Chafing-Dish and Stand, of which the following is a specification, reference being had to the accompanying drawings, forming a part hereof, in which—

Figure 1 is a plan view; and Fig. 2 is a side elevation of the design.

The design comprises a stand formed of an annulus, a plurality of straight legs, each

swelling at the top and merging into the ring, and ornamented by an elongated depressed panel, with straight sides and round ends. The legs are supported upon a base, circular in plan, with an extension adjacent to each leg, the extensions being ornamented on the sides with inward curves. The chafing dish has a cover of conical shape.

We claim:

The ornamental design for chafing-dish and stand, as shown and described.

CHARLES M. PRIOR.
CHARLES NELSON.
